CLARENCE D. PLATT, OF BRIDGEPORT, CONNECTICUT.

FUSE-PLUG.

1,215,701.

Specification of Letters Patent. Patented Feb. 13, 1917.

Application filed July 14, 1914. Serial No. 850,912.

To all whom it may concern:

Be it known that I, CLARENCE D. PLATT, a citizen of the United States, residing at Bridgeport, county of Fairfield, State of Connecticut, have invented an Improvement 5 in Fuse-Plugs, of which the following is a specification.

This invention has for its object to provide an inexpensive and efficient fuse plug 10 that will clearly indicate a "blown" or "dead" fuse. In plugs of this character it is very necessary that the fuse should be clearly visible, as the plugs are permanently sealed and there is no other practical means 15 for locating a "blown" fuse. In use, fuse plugs are commonly mounted in blocks inclosed in wall pockets or cabinets, which are necessarily often located in dark places and, as fuse plugs are now constructed, it 20 is frequently practically impossible to see through the plug windows clearly enough to detect a "blown" fuse, especially if the fuse is of low rating.

My present invention enables me to overcome 25 this objection and provide a fuse plug in which the fuse is clearly visible under all the ordinary conditions of use.

In the accompanying drawing forming a part of this specification,

30 Figure 1 is a perspective of a fuse plug embodying my novel invention;

Fig. 2 a face view with the cap removed;

Fig. 3 a face view of the base with all of the parts removed except the center contact;

35 Fig. 4 a section on the line 4—4 in Fig. 1, looking in the direction of the arrows, and

Fig. 5 is a view of the combustible disk 40 removed.

10 denotes the body which is ordinarily made of porcelain and is provided with a chamber 11 having an internal shoulder 12. The exterior of the body is provided with a 45 thread to receive the screw shell 13 and the lower end of the body is provided with the usual center contact 14. At one side of the chamber I preferably provide a groove 15 and on the opposite side of the body 50 from the groove I provide an opening 16 which extends downward and to the outer side of the threaded portion of the body, the lower end of the opening being covered by the screw shell, as clearly shown in Fig. 4,

the purpose of which will presently be explained. It will be seen therefore that when the fuse is intact it will be clearly visible owing to the contrasting color of the non-metallic disk, and when the fuse "blows" it will either destroy or effectively discolor 60 the disk so that the condition is readily apparent.

Upon the shoulder I place a non-metallic disk 17 of any suitable material, preferably of white or light colored paper. The disk 65 in the present instance is shown as provided with a tab which extends into opening 16 and prevents the disk from shifting, although this is not an essential feature of construction. 19 denotes the fuse which is 70 connected to the center contact in the usual manner, extends upward through the groove, then across the face of the disk and downward through the opening and is soldered to the screw shell as at 20. The upper end 75 of the plug is closed by a disk 21 of mica and a cap 22 having a central opening 23 through which the mica is exposed and which constitutes the window of the plug. The cap is shown as retained in place by 80 closing the edge thereof under a flange 24 at the upper end of the body. Whether the fuse burns out or "blows" from an overload or a short circuit, the disk, which contrasts in color with the fuse, will be 85 destroyed, or if not wholly destroyed will be charred and discolored to such an extent as to clearly indicate that the fuse is "blown."

As it is necessary that the portion of the fuse lying over the disk shall burn or 90 "blow" first I coat the portion of the fuse lying in the groove with a protecting covering, indicated by 25, as for example a mixture of plaster of Paris or whiting with water, which will protect that portion of 95 the fuse and increase its conductivity, thus insuring that when the fuse "blows", the portion lying across the surface of the disk will be destroyed first and will either 100 destroy the disk or will char or discolor it to such an extent as to show clearly through 105 the window of the plug and render it quite easy to detect a "blown" fuse even when the plugs are in a relatively dark place. This for the reason that when the plug is in operative condition the white disk shows clearly through the window and the destruction or charring and discoloration of

the disks indicates clearly that the fuse is "blown" even where the fuse itself would not be visible.

Having thus described my invention I claim:

1. A fuse block comprising a substantially cup-shaped insulating body providing a longitudinally-elongated and centrally-disposed chamber therein, said chamber being provided with an internal shoulder, a window of transparent material closing the open end of said chamber, a center contact in the closed end of said chamber, a screw shell inclosing a portion of said body, a tell-tale disk of inflammable material resting upon said shoulder, and a fuse having one end attached to said center contact and the other end attached to said screw shell, an intermediate portion of said fuse being extended transversely across the outer face of said tell-tale disk.
2. A fuse block comprising a substantially cup-shaped insulating body providing a longitudinally-elongated and centrally-disposed chamber therein, said chamber being provided with an internal shoulder, a window of transparent material closing the open end of said chamber, a center contact in the closed end of said chamber, a screw shell inclosing a portion of said body, a tell-tale disk of inflammable material resting upon said shoulder, and a fuse having one end attached to said center contact and passing

upwardly through said chamber and transversely across the outer face of said tell-tale disk, the portion of said fuse below the face of said disk being provided with a protective covering.

3. A fuse block comprising a substantially cup-shaped insulating body providing a longitudinally-elongated and centrally-disposed chamber therein, said chamber being provided with an internal shoulder, said chamber also being provided with a longitudinal groove and said body with an exterior channel, both said groove and said channel opening into the space within said chamber above said shoulder, a window of transparent material closing the open end of said chamber, a center contact in the closed end of said chamber, a screw shell inclosing a portion of said body and covering said channel, a tell-tale disk of inflammable material resting upon said shoulder, and a fuse having one end attached to said center contact, passing upwardly within said groove, thence transversely across the upper face of said disk and thence through said channel to connection with said shell.

In testimony whereof I affix my signature in presence of two witnesses.

CLARENCE D. PLATT.
